UNITED STATES PATENT OFFICE.

WILLIAM H. BRACEWELL, OF FISKDALE, MASSACHUSETTS, ASSIGNOR TO THE DRAPER COMPANY, OF PORTLAND, MAINE, AND HOPEDALE, MASSACHUSETTS.

END-HOLDER FOR SPINDLE-BANDS.

SPECIFICATION forming part of Letters Patent No. 645,519, dated March 13, 1900.

Application filed January 20, 1899. Serial No. 702,762. (No model.)

To all whom it may concern:

Be it known that I, WILLIAM H. BRACEWELL, of Fiskdale, county of Worcester, State of Massachusetts, have invented an Improvement 5 in End-Holders for Spindle-Bands, of which the following description, in connection with the accompanying drawings, is a specification, like letters on the drawings representing like parts.

This invention has for its object the production of a simple, easily-handled, and effective device for holding one end of a spindle-driving band when it is necessary to tie the ends of the band together, and the function 10 of the device is twofold: First, by holding one end of the band the operative is relieved from the strain due to the pull of the cylinder, as bands are usually put on when the frame is running, and, second, the measuring 15 of the strain on the band by a suitable spring-scale enables the operative to determine how much tension is being exerted as the band is applied, so that the desired tension can be applied when the band is tied.

Figure 1 is a perspective view of a portion of a spinning-frame, including the spindle-rail, the spindle-driving cylinder, and a spindle, the end-holder embodying my invention being shown in use as the band is about to be tied. Fig. 2 is a side elevation, partly in section, of the end-holder; and Fig. 3 is an inner face view of one of the end-holding jaws or gripping members.

The spindle-rail A, spindle S, having a 35 sleeve-whirl W, the spindle-base B, and the spindle-driving cylinder or drum C, Fig. 1, may be and are all of well-known or usual construction in spinning-frames.

The band-end holder embodying my invention comprises, essentially, two relatively-movable and yieldingly-connected members, one of which is adapted to engage and hold one end of the band passed around the cylinder, while the other member is held stationary by engagement with the spindle-base or any fixed part of the frame, whereby the operative, with both hands free, can adjust the tension of the band and tie its ends together.

Referring to Figs. 1 and 2, the member a is shown as a tube having a laterally-extended

projection or hook a' and a longitudinal slot a², Fig. 1, with a preferably-threaded lower end a³ to receive a tubular protective cap a⁴. Longitudinally movable within the member a I have mounted the band-holding member b, shown as a rod shouldered at its upper end at b' to rest against the adjacent end of the supporting member a and having its opposite end extended beyond the member a and threaded at b², Fig. 2, to receive an adjustable nut b³, between which and the threaded end a³ of the member a a spiral spring s surrounds the shank of the holding member. A pin or stud b⁴, fast on the member b, is extended laterally through the slot a² and carries a pointer b⁵, which co-operates with a scale M on the exterior of the member a, the spring s normally holding the shoulder b' against the end of the member a with the pointer at zero of the scale M. The member b is provided 55 with an elongated open head b⁶, at the opposite sides of which jaws b⁷ are fulcrumed nearer its outer end at b⁸, the jaws having their opposed and convex faces toothed or corrugated and offset to extend beyond the head, 60 preferably at one side, as at b⁹, as shown in Fig. 1, the jaws being inclosed within the open head and of such length that they cannot be moved outward one past the other.

When it is necessary to tie a spindle-band, 65 the operative inserts between the laterally-projecting portions b⁹ of the jaws b⁷ that end t' of the band t which will be subjected to tension by the pull of the cylinder C and catches the hook a' of the member a, preferably around 70 the spindle-base B below the whirl. The free end t' of the band is then grasped by the operative and pulled until the pointer b⁵ indicates by its position on the scale M the tension desired, and the knot is tied, it being understood that when the free end of the band is strained the member b will move relatively to the member a, the spring s being compressed proportionately to the strain. The scale M can be readily graduated to indicate 75 tensile strain on the band in pounds, and when the desired tension is indicated the operative ties the ends of the band together. By a slight lateral pull away from the side of the holding device toward the spindle the band 80

is readily released from the jaws b^7 , and then the device is unhooked from the spindle-base.

The greater the pull on the band when engaged by the jaws the more firmly will they 5 hold it, as they are thus drawn toward each other, the strain being transmitted through their fulcra to the sliding member b .

By moving the nut b^8 the tension of the spring s can be adjusted as desired, while the 10 cap a^4 protects the spring from injury and serves as a handle for the device.

My invention is not restricted to the construction and arrangement shown, for, so far as I am aware, my invention is broadly new.

15 Having fully described my invention, what I claim, and desire to secure by Letters Patent, is—

1. An end-holder for spindle-bands, comprising relatively-movable members, clamping-jaws carried by one member and adapted to engage the band end and an open hook on the other member, to be temporarily held by a fixed object, and a yielding connection between said members, the relative movement 25 of said members being determined by the pull or strain of the band.

2. An end-holder for spindle-bands, comprising a member having a rigidly-attached, laterally-extended hook adapted to engage a 30 spindle-base, a coöperating member movable longitudinally, a clamping device thereon to

engage the band end, a spring connecting said members and resisting their relative longitudinal movement, and means mounted on the movable member to adjust the tension of 35 the spring.

3. An end-holder for spindle-bands, comprising a tubular member having a hook extended laterally therefrom, a coöperating member extended through and longitudinally 40 movable in the tubular member at one end thereof, clamping-jaws on the movable member, and a spring at the other end and connecting said members and adapted to resist their relative longitudinal movement. 45

4. An end-holder for spindle-bands, comprising relatively-movable members, one of said members having a laterally-extended hook thereon, an open head on the other member, clamping-jaws mounted on said 50 head to swing within it and extended laterally beyond it, a spring connecting and adapted to resist relative movement of said members, and means to measure the extent of such movement.

In testimony whereof I have signed my name to this specification in the presence of two subscribing witnesses.

WILLIAM H. BRACEWELL.
